O. HEINIGKE.

CARPET.

No. 18,154.

Patented Mar. 6, 1888.

UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 18,154, dated March 6, 1888.

Application filed January 26, 1888. Serial No. 262,085. Term of patent 3½ years.

To all whom it may concern:

Be it known that I, OTTO HEINIGKE, of New Utrecht, Long Island, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

15 My design consists of the figures A, B, C, and D and their inclosing frame-work, all disposed over the surface of the carpet, substantially as shown.

Figure A has an open geometrical center-piece, on either side of which extends a conventionalized stem-work carrying small flower and leaf forms. This stem is angular in character, and the star-shaped flower forms are arranged upon this stem-work with more or less regularity.

Figure B has an open geometrical center-piece, around which extend several conventionalized stems carrying small flower and leaf forms. The two sides of the figure are symmetrical. On either side is a straight stem with short branches and a curved stem supporting the small star-shaped flowers.

Figure C has an open geometrical ornament at the center, on either side of which is a conventional circular flower form. There is also

a curving stem-work with branches on each side supporting little groups of leaf forms with a gem-shaped flower in each group.

Figure D has an open geometrical ornament at the center. This is encircled by a wreath 40 formed of small sprays, each spray composed of a few pointed leaves with a circular flower form at the center.

These figures are arranged upon a common groundwork divided into panels by the framework of the design. 45 This frame-work is made up of chain-like figures, at the crossings of which are large geometrical figures. Half-way between these large geometrical figures and on the chain-work are smaller irregular circular 50 figures containing each an angular volute. On some of the chains this irregular circular figure is replaced by a leaf figure.

What I claim as new, and desire to secure by Letters Patent, is—

1. The design for carpets, consisting of the figure A, substantially as shown.

2. The design for carpets, consisting of the figure B, substantially as shown.

3. The design for carpets, consisting of the figure C, substantially as shown.

4. The design for carpets, consisting of the figure D, substantially as shown.

5. The design for carpets, consisting of the figures A, B, C, and D and the frame-work, 65 substantially as shown.

OTTO HEINIGKE.
